UNITED STATES PATENT OFFICE.

WALTER S. CARPENTER, JR., OF WILMINGTON, DELAWARE, ASSIGNOR TO E. I. DU PONT DE NEMOURS POWDER COMPANY, OF WILMINGTON, DELAWARE, A CORPORATION OF NEW JERSEY.

STARTER FOR PRIME MOVERS.

1,229,584.

Specification of Letters Patent. Patented June 12, 1917.

Application filed June 8, 1912. Serial No. 702,608.

To all whom it may concern:

Be it known that I, WALTER S. CARPENTER, Jr., of Wilmington, in the county of New Castle, and in the State of Delaware, 5 have invented a certain new and useful Improvement in Starters for Prime Movers, and do hereby declare that the following is a full, clear, and exact description thereof:

The object of my invention has been to 10 provide means by which any prime mover may be conveniently started so as to enable it to continue in operation under its own power. More particularly, the object of my invention has been to provide such a means 15 having, among others, any or all of the following advantages: that it shall provide a piston, or other movable pressure-resisting device, moving or having a component of motion about the axis of the prime mover 20 shaft, or one related to such shaft; that it shall provide for the moving of such piston by the explosion of a mixture having any 25 of the three physical states, or the expansive force of any compressed gas; that it shall permit the use of the expansive force of ordinary explosives, such as gunpowder, and especially in the convenient form of gun cartridges, and that it shall be relatively 30 simple and practically automatic in its operation, and to such ends my invention consists in the means for starting prime movers hereinafter specified.

In the accompanying drawings

Figure 1 is a side view of one embodiment 35 of my invention, the lower half being in elevation, and the upper half in section on the line 1—1 of Fig. 2;

Fig. 2 is an end view, the lower half being in elevation and the upper half being in section 40 on the line 2—2 of Fig. 1;

Fig. 3 is a vertical sectional view on the line 3—3 of Fig. 2;

Fig. 4 is a top plan view; and

Fig. 5 is a sectional view of the magazine 45 and adjacent parts, showing how the shell may be blown out after it has been fired.

While I have chosen as the best embodiment of my invention known to me, the embodiment thereof shown in the drawings, 50 it is to be understood that such embodiment is typical only of many possible embodi-

ments, and that my invention is not to be confined to the particular embodiment, but also includes the principles and ideas underlying that embodiment, and which are capable of embodiment in many different forms.

The illustrated embodiment is intended especially for application to an explosive engine of the ordinary type used on automobiles, consisting of a piston and cylinder, or a series of pistons and cylinders, connected with the crank shaft 1. I have fastened on the said shaft, as by keying, a member 2 to which my starter is to apply 55 its power, such member in the present instance being a brake-disk or wheel. A casing 3 is mounted on the shaft and, at least during the starting operation, is held from rotation with the said shaft, as by being 60 fastened to a stationary part of the automobile. The said casing preferably has a bushing 4 with end plates 4^a and 4^b to provide 65 against wear by the shaft. Said frame preferably consists of a hub 5 carrying a disk 70 6, and having at its outer edge a flange 7. A rotatable part 8 is journaled preferably 75 on, but not secured to some cylindrical part of the starter, in the present instance, on the hub 5 of the frame, and the said rotatable 80 part is preferably provided with such a connection with the member 2 (which is secured to the shaft), that when the member 8 is rotated in a forward direction, it will 85 carry the disk 2 with it, but when the member 8 ceases to be propelled by the explosive 90 hereinafter mentioned, the said connection will cease to operate, so that the member 8 may remain at rest, except when it is actually starting the engine. In the present 95 instance I have illustrated the connection between the members 8 and 2 as that of the well-known brake or friction band. The band 9 passes loosely around the disk 2 and has its ends secured, as by pins 10 and 11, to 100 a lever 12, which is pivoted at its outer end to the member 8. The piston disk carries a saddle part in the form of an annular rib 8^a supporting a flange 8^b, which flange supports an outer end of the pintle of the levers 12 and also serves as a guide to keep the outer lever 12 in position. As the pins 10

and 11 are at different radial distances from the fulcrum of the lever, when the member 8 carries forward the fulcrum of the member 8, the lever swings and draws the ends 5 of the bands relatively in opposite directions, thus causing it to shorten and to grip the disk 2. In this manner the member 8 locks the disk 2 to itself and carries it forward so long as the member 8 swings forward, but, upon stopping the member 8, the 10 brake band is automatically loosened by the swinging of the inner end of the member forward, thus leaving the two members free from each other. In order to return the 15 member 8 to its initial position, after the motor has been started, a spring, such as the coil spring 13, connects it with the plate 4, which is attached to the stationary hub of the frame, one end of the spring being 20 mounted on the pin 14 on the member 2, and the other end of the spring being mounted on the pin 15 on the said plate 4⁰, the coil of the spring passing around the hub of the member 8.

25 In order to avoid any possibility of a dead center in my starter, I wish to cause the piston, which I use to move the member 8, to travel about the shaft, instead of toward and from it. For that purpose I have 30 formed an annular piston chamber 16 in the frame, which may be of any desired shape in cross-section. In the present instance it is rectangular in cross-section. In the said chamber is a piston 17 which, for a reason 35 to be later explained, is preferably slightly smaller than the cross-section of the said chamber. The said piston is carried on the member 8, and for that purpose the annular piston cylinder is formed as a groove in 40 the flange 7, so that its outer wall and its right-hand wall, as seen in Fig. 2, are formed in the said flange, and its left-hand wall is formed by the face of the frame. This leaves the bottom or inner wall of the 45 groove open. In order to close the open bottom of the annular piston cylinder, so that gases may not escape through it, I preferably make the member 8 in the form of a disk whose radius is that which the inner wall or bottom would have if it were 50 present. A ring 18 is screwed inside of the flange, having a screw-thread engagement 19, and this ring retains the piston disk 8 in its position against the face of the frame, 55 and also tends to prevent the escape of gas along the face of the said disk 8. By this construction the piston can be carried by the disk and can travel throughout the length of its annular cylinder, and yet the 60 piston is maintained sufficiently gas-tight for my purposes by means of the disk 8 closing the inner wall and forming the bottom of the said cylinder.

In order to close one end of the cylinder 65 and form an abutment against which the

propelling gases may react, I form a block 20 on the frame and extending across the cylinder.

My piston may be propelled by compressed gases derived from any source. I 70 prefer to derive them by the explosion of an explosive mixture with any of the three physical forms, that is, solid, liquid or gaseous. To enable my starter to utilize the most convenient form of explosive known 75 to me, I have adapted it for using cartridges, such as are used for fire-arms. The mechanism for such purpose can be exceedingly simple and easy to operate.

For this purpose I provide a block to 80 carry the cartridge and preferably in the form of an annular magazine 21, the said magazine having a series of chambers 22 formed therein adapted to receive cartridges. The magazine preferably bears or 85 is journaled upon the ring 18, and one face of the ring bears against the flange 7, while its other face is engaged by a ring 23 which slips over and is secured to the outer periphery of the flange, thus retaining and confining the magazine ring. The ring 23 has an opening which is closed by a plug 24 to 90 permit the introduction of cartridges into the chambers 22 to load the magazine. On its outer periphery the magazine has a series of teeth or notches 25 by which it can be moved and by which it can also be held in adjusted position. To move the magazine a bar 26 is provided, which is guided as by slots formed in a bracket 27 that is 95 fastened to the ring 23. The said bar carries a pawl 28 which is pressed toward the magazine ring by a spring 29 fastened to the bar 26, as by screws 30. The bar 26 can be moved in one direction manually, and is 100 automatically returned in the reverse direction by a spring 30^a.

In order to fire the cartridge, the following mechanism is provided: The usual retracted firing-pin 31 is mounted in the ring 110 23 and is adapted to be struck by a hammer 34 pivoted on a fixed part, the upper end of the hammer being pressed outward by a spring-pressed bolt 35. A cocking bar 36 is provided with a hook adapted to engage a 115 shoulder on the upper end of the hammer so that when the lever is moved to the left, as seen in Fig. 2, the hammer will be retracted and then tripped and allowed to be forced against the firing-pin by the spring-pressed 120 bolt 35. In order to retract the cocking bar, it is provided with a pin 37, preferably having an anti-friction roller on it, which roller is seated in and moved by a slot 38 in a plate 39, the latter being carried in 125 unison with the bar 26, as by a post 40 connecting them. When the bar 39 moves, its cam slot 38 will retract the cocking bar 36 causing it to trip the hammer.

For the purpose of ejecting the cartridge, 130

a pipe 41 connects the annular piston cylinder, at a point near the exhaust port 42, with a port 43 which is in line with the position occupied by the cartridge shell after it 5 has been fired and a new cartridge has been moved into position.

For the purpose of stopping the piston, after it has done its work, a buffer, which in 10 the present instance is shown in the form of a rubber block 44, is mounted next the abutment block 20.

In the operation of the illustrated embodiment of my starter, the rod 26 is pressed to the right, as seen in Fig. 3, moving the 15 magazine one step, a spring-pressed centering pin 45 rising out of one of the peripheral notches on the magazine and dropping into another during this operation, thus holding the magazine with a cartridge in 20 line with the passage 46 opening between the abutment and the piston. The movement of the bar 26 cocks the hammer and releases it, after the magazine has been moved and positioned, and the hammer thus 25 explodes the cartridge. The gases of combustion rush through the passage 46 (a cartridge being in line with the passage 46) and propel the piston to the left, as seen in Fig. 1, causing it to travel around its annular passage until it has passed the exhaust 30 port 42, at which point the gases exhaust, some of the gases just previously having passed through the pipe 41 and out through the port 43, ejecting the previously fired 35 empty shell (which has been moved to a position opposite the said port 43), the shell being blown out through a hole in the casing 23, as shown in Fig. 5, the casing being complete at either point to prevent escape 40 of the shells. The piston continues until it strikes the buffer, and its force having been spent, it is returned by the coil spring 13 to initial position, the piston preferably being slightly loose so as not to trap air or 45 gases behind it. The travel of the piston, carrying with it the disk 8, causes the friction band to grip the friction disk and thus causes the shaft 1 to be turned, starting the engine so that it may continue under its 50 own power.

It will be seen that my invention provides a very convenient means for starting automobile engines and other prime movers. As the explosion of a cartridge is easy and certain, my starter can always be counted on and does not become inactive through the leakage of compressed air or gas, or some other defect with other forms of stored-up power. It is to be understood, however, 55 that the principles of my invention are many and are applicable to other forms of power than that of a cartridge.

I claim—

1. In a starter for prime movers, the 60 combination of a shaft, a casing having an

annular cylinder formed therein, a disk loosely mounted on said shaft and entering said cylinder through a slot, a piston in said cylinder carried by said disk, an abutment in said cylinder, a friction wheel fast 70 on said shaft, a clutch-strap and lever, the strap surrounding said wheel, and the lever being connected to said disk.

2. In a starter for prime movers, the combination of a shaft, a casing having an annular cylinder formed therein, a disk loosely mounted on said shaft and entering said cylinder through a slot, a piston in said cylinder carried by said disk, an abutment in said cylinder, a friction wheel fast on 75 said shaft, a clutch-strap and lever, the strap surrounding said wheel, the lever being connected to said disk, and an exhaust port in said cylinder on the opposite side of said piston from said abutment, said piston 80 loosely fitting said cylinder.

3. A starter for prime movers, comprising a shaft, an annular cylinder concentric with said shaft, a piston and an abutment in said cylinder, means for holding and exploding a cartridge, means for conducting the gases of combustion between said piston and abutment, and means for admitting said gases to eject a previously discharged cartridge. 90

4. A starter for prime movers, comprising a shaft, an annular cylinder concentric with said shaft, a piston and an abutment in said cylinder, a clutch connection between said piston and said shaft, an annular magazine 100 adapted to contain cartridges, means for holding one chamber of said magazine in line with a passage leading between said piston and abutment, means for firing a cartridge in said chamber, and means for advancing said magazine to bring a fresh cartridge into firing position, said means for advancing being connected with said firing means so as to be operated thereby. 105

5. A starter for prime movers, comprising a shaft, an annular cylinder concentric with said shaft, a piston and an abutment in said cylinder, a clutch connection between said piston and said shaft, an annular magazine 110 adapted to contain cartridges, means for holding one chamber of said magazine in line with a passage leading between said piston and abutment, means for firing a cartridge in said chamber, and means for conducting the gases of combustion to the position of the previously discharged cartridge 115 to eject the latter. 120

6. A starter for prime movers, comprising a shaft, an annular cylinder concentric with said shaft, a piston and an abutment in said cylinder, a clutch connection between said piston and said shaft, an annular magazine concentric with said shaft and adapted to carry a series of cartridges, said magazine being provided with a series of shoulders,

means to engage said shoulders to position a cartridge in line with a passage leading between said piston and abutment, a part adapted to be manually moved and carrying 5 means for engaging and advancing said magazine, and means for firing said cartridge.

7. A starter for prime movers, comprising a shaft, an annular cylinder concentric with 10 said shaft, a piston and an abutment in said cylinder, a clutch connection between said piston and said shaft, an annular magazine concentric with said shaft and adapted to carry a series of cartridges, said magazine 15 being provided with a series of shoulders, means to engage said shoulders to position a cartridge in line with a passage leading between said piston and abutment, a part adapted to be manually moved and 20 carrying means for engaging and advancing said magazine, and means for firing said cartridge, said magazine advancing means comprising a bar manually movable against spring-pressure, and having a spring-pawl 25 adapted to engage said shoulders on said magazine.

8. A starter for prime movers, comprising a shaft, an annular cylinder concentric with 30 said shaft, a piston and an abutment in said cylinder, a clutch connection between said piston and said shaft, an annular magazine concentric with said shaft and adapted to carry a series of cartridges, said magazine being provided with a series of shoulders, 35 means to engage said shoulders to position a cartridge in line with a passage leading between said piston and abutment, a part adapted to be manually moved, and carrying means for engaging and advancing said 40 magazine, and means for firing a cartridge, said means comprising a bar manually movable against spring-pressure and having a spring-pawl adapted to engage said shoulders on said magazine, said firing means 45 comprising a hammer and a part for tripping said hammer and connections between said parts and said bar.

9. A starter for prime movers, comprising a shaft, an annular cylinder concentric with 50 said shaft, a piston and an abutment in said cylinder, a clutch connection between said piston and said shaft, an annular magazine concentric with said shaft and adapted to carry a series of cartridges, said magazine 55 being provided with a series of shoulders, means to engage said shoulders to position a cartridge in line with a passage leading between said piston and abutment, a part adapted to be manually moved, and carrying 60 means for engaging and advancing said magazine, means for firing a cartridge, said means comprising a bar manually movable against spring-pressure and having a spring-pawl adapted to engage said shoulders on 65 said magazine, said firing means comprising

a hammer and a part for tripping said hammer and connections between said parts and said bar, said connections consisting of a plate carried by said bar and having a cam-slot therein and a pin on said tripping part 70 and engaged by said cam.

10. A starter for prime movers, comprising a shaft, an annular cylinder concentric with said shaft, a piston and an abutment in said cylinder, a clutch connection between 75 said piston and said shaft, an annular magazine concentric with said shaft, means for yieldingly holding said magazine with one of its chambers in line with a passage leading between said piston and abutment, said magazine having shoulders formed thereon, a spring-pressed bar slidably mounted tangentially to said magazine and carrying a pawl adapted to engage said shoulders, a hammer adapted to engage the cartridge in 80 operative position, a tripping bar movable transversely to said spring-pressed bar for tripping said hammer, a part carried by said spring-pressed bar and having a cam slot and a pin on said tripping bar and engaged 85 by said cam slot.

11. A starter for prime movers, comprising a shaft, an annular cylinder concentric with said shaft, a piston and an abutment in 90 said cylinder, a clutch connection between said piston and said shaft, an annular magazine concentric with said shaft, means for yieldingly holding said magazine with one of its chambers in line with a passage leading between said piston and abutment, said magazine having shoulders formed thereon, a spring-pressed bar slidably mounted tangentially to said magazine and carrying a pawl adapted to engage said shoulders, a hammer adapted to engage the cartridge in 100 operative position, a tripping bar movable transversely to said spring-pressed bar for tripping said hammer, a part carried by said spring-pressed bar and having a cam slot 105 and a pin on said tripping bar and engaged by said cam slot, and a passage for conveying 110 gases from said cylinder to eject the cartridge previously fired.

12. In a starter for prime movers, the combination of a shaft, a cylinder and piston 115 for starting said shaft, a clutch connection between said piston and said shaft, a magazine for carrying a plurality of cartridges, means for positioning said magazine so that one of said cartridges shall communicate 120 with the passage between said piston and abutment, and a passage for conveying the gases of combustion to the position of a previously exploded cartridge to eject the latter.

13. In a starter for prime movers, the combination of a shaft, a frame having a surface perpendicular to the shaft, and having an annular flange parallel to the shaft, a piston disk bearing against said first men- 130

tioned disk and within said flange, a piston on the edge of said disk, and a ring adapted to be screwed within said flange to inclose said piston disk.

5 14. A starter for prime movers, comprising a shaft, an annular cylinder concentric with said shaft, a piston and an abutment in said cylinder, a magazine adapted to contain cartridges, means for holding one chamber of said magazine in line with a passage leading between said piston and abutment, means for firing a cartridge in said chamber, and means for advancing said magazine to bring a fresh cartridge into firing position, said means for advancing being connected with said firing means so as to be operated thereby.

15 15. A starter for prime movers, comprising a shaft, an annular cylinder concentric with said shaft, a piston and an abutment in said cylinder, a magazine adapted to contain cartridges, means for holding one chamber of said magazine in line with a passage leading between said piston and abutment, means for firing a cartridge in said chamber, and means for conducting the gases of combustion to the position of the previously discharged cartridge to eject the latter.

20 16. A starter for prime movers, comprising a shaft, an annular cylinder concentric with said shaft; a piston and an abutment in said cylinder, a magazine adapted to carry a series of cartridges, said magazine being provided with a series of shoulders, means to engage said shoulders to position a cartridge in line with a passage leading between said piston and abutment, a part adapted to be manually moved and carrying means for engaging and advancing said magazine, and means for firing said cartridge.

25 17. A starter for prime movers, comprising a shaft, an annular cylinder concentric with said shaft, a piston and an abutment in said cylinder, a magazine adapted to carry a series of cartridges, said magazine being provided with a series of shoulders, means to engage said shoulders to position a cartridge in line with a passage leading between said piston and abutment, a part adapted to be manually moved and carrying means for engaging and advancing said magazine, and means for firing said cartridge, said magazine advancing means comprising a bar manually movable against spring-pressure, and having a spring-pawl adapted to engage said shoulders on said magazine.

30 18. A starter for prime movers, comprising a shaft, an annular cylinder concentric with said shaft, a piston and an abutment in said cylinder, a magazine adapted to carry a series of cartridges, said magazine being provided with a series of shoulders, means to engage said shoulders to position

a cartridge in line with a passage leading between said piston and abutment, a part adapted to be manually moved, and carrying means for engaging and advancing said magazine, and means for firing a cartridge, 70 said means comprising a bar manually movable against spring-pressure and having a spring-pawl adapted to engage said shoulders on said magazine, said firing means comprising a hammer and a part for tripping said hammer and connections between said parts and said bar.

19. A starter for prime movers, comprising a shaft, an annular cylinder concentric with said shaft, a piston and an abutment 20 in said cylinder, a magazine adapted to carry a series of cartridges, said magazine being provided with a series of shoulders, means to engage said shoulders to position a cartridge in line with a passage leading 25 between said piston and abutment, a part adapted to be manually moved, and carrying means for engaging and advancing said magazine, means for firing a cartridge, said means comprising a bar manually movable 30 against spring-pressure and having a spring-pawl adapted to engage said shoulders on said magazine, said firing means comprising a hammer and a part for tripping said hammer and connections between said parts 35 and said bar, said connections consisting of a plate carried by said bar and having a cam-slot therein and a pin on said tripping part and engaged by said cam.

20. A starter for prime movers, comprising a shaft, an annular cylinder concentric with said shaft, a piston and an abutment in said cylinder, a magazine, means for yieldingly holding said magazine with one of its chambers in line with a passage leading between said piston and abutment, said magazine having shoulders formed thereon, a spring-pressed bar slidably mounted tangentially to said magazine and carrying a pawl adapted to engage said shoulders, a 105 hammer adapted to engage the cartridge in operative position, a tripping bar movable transversely to said spring-pressed bar for tripping said hammer, a part carried by said spring-pressed bar and having a cam 110 slot and a pin on said tripping bar and engaged by said cam slot.

21. A starter for prime movers, comprising a shaft, an annular cylinder concentric with said shaft, a piston and an abutment 115 in said cylinder, a magazine, means for yieldingly holding said magazine with one of its chambers in line with a passage leading between said piston and abutment, said magazine having shoulders formed thereon, 120 a spring-pressed bar slidably mounted tangentially to said magazine and carrying a pawl adapted to engage said shoulders, a hammer adapted to engage the cartridge in operative position, a tripping bar movable 125

transversely to said spring-pressed bar for tripping said hammer, a part carried by said spring-pressed bar and having a cam slot and a pin on said tripping bar and engaged by said cam slot, and a passage for conveying gases from said cylinder to eject the cartridge previously fired.

In testimony that I claim the foregoing I have hereunto set my hand.
